UNITED STATES PATENT OFFICE.

ELMER GRAHAM, OF WRAY, COLORADO.

BOOK-HOLDER.

1,281,776.

Specification of Letters Patent.

Patented Oct. 15, 1918.

Application filed April 10, 1917. Serial No. 160,976.

To all whom it may concern:

Be it known that I, ELMER GRAHAM, a citizen of the United States, and resident of Wray, in the county of Yuma and State of Colorado, have invented a new and Improved Book-Holder, of which the following is a full, clear, and exact description.

This invention relates to bookholders and has particular reference to a device of this character intended for holding heavy volumes from which typewritten copies are to be made, as for example in abstract offices.

Among the objects of the invention is to provide a holder for large and heavy books, so constructed that the book will always lie open flat irrespective of the thickness of the book or the proximity of the work to be copied to either of the back boards.

Another object of the invention is to improve the various details of construction including the line gage devices and the counter balancing means for the book rest adapting the same to be elevated or lowered as may be desired.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views and in which

Figure 1 is a front elevation of a preferred embodiment of the invention, the book-rest being elevated and the line gage device being extended upwardly as in operating position.

Fig. 2 is a side elevation looking toward the left in Fig. 1 and with parts broken away to show the construction.

Fig. 3 is a vertical sectional view of the counter balancing drum on the line 3—3 of Fig. 4.

Fig. 4 is a horizontal section on the line 4—4 of Fig. 3.

Fig. 5 is a transverse sectional detail of the line gage bracket on the line 5—5 of Fig. 2.

Fig. 6 is a longitudinal section view of the same.

Fig. 7 is approximately a plan view of

the device as seen in the direction of the arrow 55 7 in Fig. 2; and

Fig. 8 is a rear perspective view of the book-rest supporting means.

Referring now more particularly to the drawings I show at 10 a rigid supporting frame of any suitable design or material, but indicated as comprising a plurality of feet 11 and 12 and rear legs 13 braced to the front foot portions by means of braces 14. The frame also includes an upwardly projecting runway 15 comprising two parallel bars U-shaped in cross section, as shown in Fig. 7. These bars are connected at their upper ends by a yoke 16 and are anchored at their lower ends to a pair of brackets 17 leading laterally to the front feet 11. The concave sides of the bars 15 are faced toward each other providing a channel or guideway for a carrier 18 which constitutes the main portion of my invention.

Said carrier comprises an upwardly projecting rib 19 having rearwardly projecting pintles 20 and 21 on which are journaled a pair of anti-friction rollers 22 having their peripheries rolling in the channels formed in the bars 15. The rear legs 13 project upwardly and forwardly merging into the bars 15 just above their middle portions and hence the frame provides a rigid supporting structure for the carrier. The engagement between the peripheries of the rollers 22 and the runway obviates all likelihood of twisting or torsional movement of the carrier with respect to the frame. The rib 19 is provided with forwardly projecting lugs 23 and 24, and the pintle 21 projects rearwardly providing a means for attaching an anchor member 25 to the carrier. Said anchor member is provided with a downwardly projecting stud 26 and an upwardly projecting ear 27.

To the lower end of the rib 19 is secured a forwardly and rearwardly extending right angularly disposed bracket 28. (See Figs. 100 5 and 6). This bracket 28 is of convexo-concave structure and upon the edges of which is mounted a slideable shoe 29 having flanges 30 overlapping the side edges of the bracket. This shoe 29 carries a leaf spring 105 31, the rear end of which is anchored within the shoe, while the outer free end constitutes a head 32 projectable through an

opening 33 in a bracket 34 constituting the base of the line gage device and pivoted at 32' to the front end of the shoe. The pivot 32' holds the outer free end or head 5 portion of the spring elevated so that when the bracket 34 is swung upwardly from the plane of the shoe the head 32 of the spring will project through the opening 33 and snap into the bottom of the opening with 10 the shoulder portions of the head engaging or interlocking with the bracket at the bottom of the opening. (See Figs. 1 and 6.) To release the line gage device to permit it to swing forwardly and downwardly, 15 the operator has but to lift up the head 32 of the spring when the line gage device will be free to swing downwardly into substantially the plane of the shoe.

The bracket 34 carries a channel member 20 34' within which are pivoted any suitable arrangement of lazy tong devices 35 to the upper end of which is connected a bar 36 constituting the line gage proper and carrying finger pieces 37 for lifting it. One or 25 more springs 31' resiliently connect the bracket 28 and the outwardly slid able shoe 29. These springs are indicated as being attached at one end to lugs 28' and at the other end to the pivot 32'. The normal tendency of the springs is to contract the bracket 30 portions of the line gage devices tending to hold the line gage bar 36 against the face of the book.

The book support comprises a pair of 35 wings 38 made of wood or any other suitable material and adapted to lie either in the same plane or in parallel planes and so mounted that either of the wings may occupy a plane in front of the plane of the other. The book support is mounted upon 40 the carrier 18 above referred to and any suitable means may be provided to connect the book support to the carrier. To this end, however, I provide a double T-shaped 45 rocker comprising an upright bar 39 to which upper and lower cross bars 40 and 41 are rigidly secured at right angles to the bar 39 and parallel to each other. This rocker device is pivoted coaxially of the bar 50 39 upon the lugs 23 and 24 whereby the book support is adapted to swing to a suitable angle around the axis of said lugs in either direction. The wings 38 are provided 55 with brackets 42 and 43 rigidly secured to their rear faces. The upper brackets 42 are pivotally connected at 44 to the ends of the cross bar 40 and the lower brackets 43 are pivotally intermediate of their ends at 45 to the ends of the cross bar 41. The brackets 60 43 are extended rearwardly, however, back of the plane of the runway 15 and to the rear ends thereof is pivotally connected at 46 a stay bar 47 which being parallel to the plane of the cross bars 40 and 41 serves to 65 maintain the wings either in the same plane

or in parallel planes. The stay bar is pivoted at its center upon the stud 26 extending downwardly from the anchor member 25. Along the rear portion of each of the wings is secured a channel member 48 adapted to 70 receive one of the book covers and at the outer ends of the channels 48 are pivoted a pair of hooks 49. Each of these hooks, as shown best in Fig. 2, is pivoted at 50 above the channel member and has a pit or recess 75 registering with the interior of the channel but is adapted to swing forwardly and upwardly from such position as shown in dotted lines in Fig. 2. The rearward swinging movement of the hooks 49 is limited by 80 an extension 51 at the lower outer corner of each wing.

The elevation of the carrier is determined by means of a strap 52 of leather or other suitable flexible material extending up and around a drum 53 and having its end secured at 54. The drum is journaled upon a shaft 55 in a casing 56 just back of the runway and at the upper ends of the rear legs. The shaft 55 is horizontal and parallel to the 90 plane of the runway, this shaft furthermore is concentric with the casing, but the drum 53 is eccentric to the shaft. The upper end of the strap at its point of connection 54 is located at the part of the drum having its 95 greatest eccentricity.

57 indicates a strong spiral spring having one end secured at 58 upon the interior of the drum and the other end secured at 59 to the shaft 55. The spring is coiled preferably around the shaft in the same direction as the strap 52 is wrapped upon the outside of the drum. The rotation of the shaft 55 in clockwise direction to increase the tension upon the spring tends to elevate the carrier 100 through the strap 52 attached to the anchor device 25. Any suitable means may be provided to vary the tension of the spring and hold the shaft normally from rotation. For this purpose I provide a crank 60 secured to 105 a counter shaft 61 journaled in the lower portion of the casing 56. A pinion 62 is fixed upon the counter shaft and meshes with a gear 63 fixed upon the main shaft 55. Upon the rotation of the crank as indicated 110 by the arrows on Fig. 2 the force of the spring is increased. After the desired tension is provided for the spring the crank 115 may be locked beneath a keeper 64 secured to one of the legs 13.

Referring now to Figs. 2 and 3 the purpose of the eccentricity of the spring drum will be appreciated. With the carrier elevated as shown in Fig. 2, the spring will be in a position where it is relatively weak, but 125 in this position the drum is so disposed that the weight of the carrier is supported upon its shortest radius. If, however, the carrier be drawn downwardly to a lower position it must be so moved against the force tending 130

- to wind the spring and consequently the drum is rotated so that such superior force of the spring is counteracted by the carrier applied to the greater radius of the drum.
- 5 By this arrangement therefore I provide that the carrier will remain elevated in any position to which it may be adjusted.
- The purpose of the hooks 49 is to support the leaves of the book which, especially when 10 the book is old and opened far toward the front or toward the back leaving most of the leaves on one side, are likely to droop or sag. The hooks hold the leaves in place taking the strain off the binding and keeping 15 the leaves in position so that the line gage will follow the line perfectly across both edges.

I claim:

1. In a bookholder, the combination of an 20 upright frame, a book-rest supported upon the frame and comprising a pair of wings against which the book backs are adapted to rest in the same plane or in parallel planes, said book-rest including a pair of 25 hooks pivoted on transverse axes to the lower portions of the wings, each hook having a recess to receive a book back and hold it close to the wing to which the hook is pivoted, and also having a forwardly projecting finger to support the free edges of 30 the leaves adjacent to such back.

2. In a bookholder, the combination of an upright frame including a pair of spaced parallel bars constituting a runway, a carrier including a plurality of anti-friction 33 rollers coöperating with said bars and movable longitudinally of the runway, a flexible member connected to the carrier, means including a variable spring acting upwardly upon the flexible member tending to elevate 40 the carrier, and a book-rest comprising a pair of wings pivoted to the carrier and means serving to hold the wings in parallel planes at variable distances from the plane of the carrier. 45

3. In a bookholder, the combination of a frame including a rigidly supported runway, a carrier anti-frictionally supported in said runway, a book-rest connected to the carrier and comprising a pair of wings to 50 support the back boards of the book in variable positions with respect to the plane of the carrier, and means connected to the frame and to the carrier tending to elevate the carrier, said last mentioned means comprising an eccentrically mounted drum and a spring secured thereto, the drum being so mounted that when the spring is strongest the carrier will act upon that portion of the drum having the greatest eccentricity. 55

ELMER GRAHAM.
